DIRECT CURRENT VOLTAGE AMPLIFIER

Wesley M. Roberds, Collingswood, and Benjamin F. Wheeler, Haddonfield, N. J., assignors to Radio Corporation of America, a corporation of Delaware

Application March 24, 1943, Serial No. 480,290

5 Claims. (Cl. 179—171)

The present invention relates to thermionic amplifiers and more particularly to an amplifier system utilizing a cathode-ray or beam deflection tube capable of amplifying small D. C. voltages.

It is one of the objects of our invention to provide an electronic amplifier which is provided with a low impedance input, which is extremely sensitive, and which develops a large output voltage with respect to its input voltage.

Another object of the invention is to effect the control of the electron stream in an electron discharge tube amplifier by means of a magnetic field.

Still another object of the invention is to cause the deflection of the cathode-ray beam produced in the tube to be controlled by the input voltage.

A further object is to pick up D. C. energy at a low voltage from a low impedance circuit and to put it out at a high impedance level whereby further amplification by ordinary electronic tubes is efficiently carried out.

A better understanding of our invention will be obtained and other objects, features and advantages will appear from the following description taken in connection with the accompanying drawing in which Fig. 1 illustrates schematically a circuit in accordance with the invention for amplifying small D. C. voltages, the magnetizing coils being external of the tube and shown for clarity as displaced through an angle of 90 degrees from their actual location; Fig. 2a is a plan view, partly in section, of the beam-deflection tube of Fig. 1, with the magnetizing coils shown in their proper location; Fig. 2b is a view similar to Fig. 2a but with the magnetizing coils contained within the tube envelope; Figs. 3a and 3b are views showing diagrammatically the deflection of the cathode-ray beam or electron stream with varying input control voltages.

Referring to Fig. 1 there is shown in cross-section an electron discharge tube 1 of the beam deflection type, comprising an evacuated receptacle 2 within which there is contained a metallic cylinder 3 suitably supported from the base end of the receptacle. The cylinder is closed at opposite ends by circular disc electrodes 4 and 5. A third circular disc electrode 6 is interposed between the latter disc electrodes but positioned closer to the electrode 5. The electrodes 4 to 6 are each provided with a slotted aperture 7 substantially of the form shown in Fig. 2a, the several apertures being in alignment as shown. A cathode or electron emitter 8 of the indirectly heated type is positioned externally of the cylinder 3 and close to the aperture of the electrode 5.

5, and an anode or electron collector 9 is positioned externally and adjacent the aperture of electrode 4. In the space between the disc electrodes 4 and 6 and on opposite sides of a median line passing through the electrode apertures are

5 a pair of static deflecting plates 10 and 11 disposed in parallel relation. The cathode 8 and the apertured electrodes 5 and 6 constitute an electron gun which as is well known produces a thin ribbon-like electron beam which passes between the deflecting plates 10 and 11 and through the apertured electrode 4 and finally impinges upon the anode or collecting electrode 9.

For connection to external circuit elements,

15 individual lead-in conductors 8', 9', 10' and 11' are provided respectively for the cathode, the anode and the static deflecting plates. The apertured electrodes 4, 5 and 6 and the metallic cylinder 3 to which they are conductively connected

20 are provided with a common lead-in conductor 3' which is connected to the positive terminal of a suitable source of power supply, such as the battery 12. The cathode return or lead-in conductor 8' is connected to the negative terminal

25 of the source 12, and the deflecting electrode leads 10' and 11' which pass through suitable apertures in the cylinder 3 and through the side wall of the tube envelope 2 are connected to variable taps on the potentiometers 13 and 14 respectively.

30 A pair of magnetizing coils 15 and 16, which may be located outside the tube receptacle as shown in Fig. 2a or within the receptacle as shown in Fig. 2b, are disposed in parallel relation and laterally with respect to the tube axis.

35 The coils are so wound and electrically connected that their magnetic fields are in phase, that is in the same direction, and at right angles to the direction of travel of the electron beam. Since electrons are deflected at right angles to the

40 magnetic field through which they pass, as viewed in the drawing the electron beam will be deflected in a direction transverse to the slit in electrode 4. The voltage to be controlled and amplified is connected to a pair of terminals 45 designated "input" to which the magnetizing coils are connected.

The anode or collecting electrode 9 is connected through a pair of load resistors 17, 18 to the power supply source at a point which is lower 50 in potential by about 45 volts than that applied to the apertured electrodes 4 to 6. The high potential or anode end of the resistor 17 is connected to the control grid of a power amplifier tube 20, and the low potential end of the resistor 18 is connected to the control grid of a second

power tube 21. The battery 22 or other known means may be utilized to provide a suitable negative bias for the grids of tubes 20, 21. The resistors 23, 24, 25 are connected between the output plates of the power tubes and constitute the output load therefor. A suitable source of power supply 26 is connected between the cathodes and the resistor 24, the connection to the latter being adjustable in order that the anodes of the tubes 20 and 21 may have equal voltages impressed thereon. The amplified voltages are derived from the terminals which are designated "output" and to which may be connected a meter or other indicating device.

In the operation of the circuit above described, by means of the potentiometers 13 and 14 the voltage across the static deflection plates 10 and 11 is adjusted until the electron beam is on the very edge of the slit in electrode 4, as shown in Fig. 3a. A very small D. C. current flowing in the magnetic deflection coils 15 and 16 will produce a magnetic field, the extent of which at right angles to its direction is substantially that shown by the dotted circle, and will deflect the beam further into the slit as shown in Fig. 3b. This beam of electrons, having fallen through a potential difference of nearly 300 volts, passes electrode 4 and goes on to strike anode 9 in spite of the retarding potential of 45 volts between electrodes 9 and 4. The beam strikes 9 hard enough to knock out showers of secondary electrons. These secondaries, once freed from their parent electrode are drawn to the more positive electrode 4.

The electrons passing from 9 to 4 constitute an electric current which returns to 9 via the portion 27 of the battery 12 and the resistors 18 and 17. Thus when this current is flowing, the grid of tube 21 is made negative with respect to its cathode and the grid of tube 20 is made positive with respect to its cathode. Therefore the plate current of 20 is increased and that of 21 is decreased. This unbalance of currents appears in the output meter and hence the reading of an output meter connected to the output terminals is dependent upon the current which flows in the coils 15 and 16. Over an appreciable range the output current is substantially proportional to the input current.

In connection with high frequency heating and surface hardening of steel it is desired to get a graphic record of the temperature changes in the surface layers as the power is applied. Small thermo-couples will respond to such temperature changes but since the times of heating and cooling are in the order of a few tenths of a second it is difficult to obtain a recording instrument which would be fast enough in its response and still give readable deflections for the voltages developed by the thermo-couples. Several types of amplifiers and recording instruments were considered but all seemed rather clumsy or unduly complicated.

In one application of the present invention a thermo-couple was connected to the input terminals leading to the magnetizing coils, and the small D. C. potential generated by the thermo-couple was amplified a thousand fold. The thermo-couple, being a low impedance device cannot be coupled efficiently to the control grid of a conventional amplifier tube neither directly, because of the great difference in impedance of the two circuits and because contact potentials in a thermionic grid circuit are of the same order of magnitude as the thermal E. M. F.'s, nor

indirectly through a transformer since the thermo-couple voltages are D. C. However by connecting a thermo-couple or other low impedance source to the low impedance magnetizing coils the resulting current will cause magnetic fields sufficiently large to deflect the electron stream of the beam deflection tube in the manner explained above and thus efficiently control the voltage in the output circuit of that tube.

10 From this output circuit (which is of high impedance) it is easy to couple efficiently to further stages of amplification in the conventional manner.

The combined resistance of the coils, each of 75 turns of No. 22 copper wire, was about the same as that of the thermo-couple so that the magnetic effect of the comparatively large currents flowing in the coils is capable of being used to measure the E. M. F.'s developed by the thermo-couple.

15 While we have shown and described a preferred embodiment of our invention, it will be understood that various modifications and changes will occur to those skilled in the art without departing from the spirit and scope of this invention. 20 We therefore contemplate by the appended claims to cover any such modifications as fall within the true spirit and scope of our invention.

What we claim is:

30 1. A circuit for the amplification of small D. C. voltages comprising a pair of input terminals to which the D. C. voltages to be amplified are applied, an electron discharge tube provided with a plurality of electrodes constituting an electron 35 gun for producing an electron beam, an anode and an apertured electrode positioned in front of the anode, a first means adapted in the absence of an input voltage to deflect the electron beam so that it impinges substantially entirely on the 40 apertured electrode, a second means connected to the input terminals and responsive to input voltages impressed thereon for deflecting the electron beam so that varying amounts of the electrons are caused to impinge on the anode, 45 and a circuit including a utilization device connected to the anode.

2. A circuit in accordance with the invention defined in claim 1 wherein the second beam deflecting means is disposed externally of the tube.

50 3. A circuit in accordance with the invention defined in claim 1 wherein the second beam deflecting means is disposed within the tube.

4. A circuit for the amplification of small D. C. voltages comprising a pair of input terminals to

55 which the D. C. voltages to be amplified are applied an electron discharge tube provided with a plurality of electrodes constituting an electron gun for producing an electron beam, an anode and an apertured electrode positioned in front of the anode, means adapted in the absence of an input voltage to deflect the electron beam so that it impinges substantially entirely on the apertured electrode, magnetic means connected to the input terminals and responsive to the input voltages impressed thereon arranged to produce a magnetic field at right angles to the electron beam and for deflecting the electron beam so that varying amounts of the electrons are caused to impinge on the anode, and a circuit 60 including a utilization device connected to the anode.

65 5. A circuit for obtaining high amplification of small D. C. voltages comprising a pair of input terminals to which the D. C. voltages to be amplified are applied an electron discharge tube pro-

vided with a cathode, an anode and a plurality of apertured electrodes interposed therebetween, said cathode and certain of the apertured electrodes constituting an electron gun for producing an electron beam between cathode and anode, a first means adapted in the absence of an input voltage to deflect the electron beam so that it impinges substantially entirely on the apertured electrode, a second means connected to the

input terminals and responsive to input voltages impressed thereon for deflecting the electron beam so that varying cross-sectional areas of the electron beam are caused to impinge on the anode, and a circuit including a load connected between the anode and cathode.
